UNITED STATES PATENT OFFICE.

LEOPOLD STEINER, OF BROOKLYN, NEW YORK, ASSIGNOR TO JOHN M. OHLENBUSCH,
OF NEW YORK, N. Y.

HAIR CURLER.

Application filed January 24, 1925, Serial No. 4,473. Renewed May 14, 1928.

This invention relates more especially to that type of hair curler in which relatively rotatable parts are employed to impart a final twist to a lock of hair coiled about the 5 curler. In the use of a hair curler of this character, it is customary to secure a lock of hair at a point near the scalp to one of the relatively rotatable parts, after which the loose end of the lock is coiled closely around 10 the curler and secured at its outer end to the other part of the curler. The final twist or tightening of the lock of hair on the curler is then secured by a relative rotation of the parts.

15 The object of my invention resides more especially in the provision of an improved construction in the means for imparting the relative rotation to the parts and an improved construction for releasably locking 20 the parts together.

More specific objects of invention will appear in the specification and be pointed out in the appended claims, reference being had to the accompanying drawings which 25 exemplify my invention in a preferred embodiment.

In the drawings:

Figure 1 is a perspective view showing an adaptation of my invention to a hair curler 30 of the double spindle type.

Figure 2 is an axial section of the same; parts being shown in elevation.

Figure 3 is a perspective view of the inner spindle with the parts separated and in position to be assembled; and

Figure 4 is a section on the line 4—4 of Figure 2.

According to the embodiment of my invention shown on the drawings, the relatively 40 rotatable members or parts of the hair curler comprise on the one hand an outer tubular spindle 1, and on the other hand an inner spindle including a rod 2 connected at one end by screw threads 3 to a turning head 4 and 45 at its other end by means of screw threads 5 to a twisting head 6 provided with a slot 7. This slot 7 is provided in order that one end of the lock of hair, the end near the scalp, may be more readily secured thereto.

50 As shown in Figure 2, the twisting head 6 is provided with a reduced neck 8 upon which the hollow spindle 1 journals at one end. The cylindrical outer surface of the turning

head 4 constitutes a journal for the other end of said spindle 1.

Said outer spindle 1 is preferably tapered as shown; and at its larger end is enlarged to form a cylindrical elongated flange 9 which as shown in Figures 1 and 2, is provided with end recesses 10 which latter are preferably in the form of radial slots. Obviously, the portion 9 could be constructed as a separate piece and be secured rigidly to the tube 1 by screw threads or other suitable means.

The turning head 4 of the inner spindle is provided with an extended axial slot 11 (see Figure 3), which may be moved into and out of register with any of the end recesses 10 of relatively rotatable member 1. A pin 12 mounted in the bifurcated end of turning head 4, and traversing the slot 11 therein, serves as a pivot for a finger grip or piece 13 which is thereby adapted to swing into and out of interlocking engagement with any one of the recesses 10 which may happen to be in register with the slot 11.

In operation, a lock or tress of hair of about the same thickness as the curler is taken, and the inner end thereof, that is, the 80 end close to the scalp, is tied to the end 6 of the inner spindle, making use in this connection of the slot 7. After this has been done, the lock or tress is wrapped or coiled around the outer spindle and then secured at its free 85 end to the tube 1 or its enlarged end or collar 9. To give the final tightening of the hair on the curler, the turning head 4 is rotated by finger grip 13 to the extent desired, and the inner rotatable member is then locked to the 90 outer rotatable member by moving the finger grip 13 about its axis 12 into the dotted line position (shown in Figure 2) in which it engages a slot 10.

While I have described my invention in 95 detail in order to assure a clear understanding of the same, it will be obvious that modifications may be made without departing from the spirit thereof.

I claim:

1. A hair curler comprising two relatively 100 rotatable spindles having portions arranged one within the other, one of said spindles being provided at an end with a locking recess, the other spindle extending beyond the first-named spindle at said end, and means pivot-

- ally mounted on said extension on an axis transverse to the spindle and rotatable about said axis into engagement in said recess to lock said two spindles against relative rotation.
2. A hair curler comprising relatively rotatable spindles provided with recesses movable into and out of registry with each other, and means movable into and out of position to engage the walls of said recesses in registered relation for locking said spindles against relative rotation.
3. A hair curler comprising relatively rotatable spindles having portions arranged one within the other, said portions of the respective spindles being provided with recesses movable into and out of registry with each other, and means adapted to engage in said recesses in registry with each other for locking said spindles together.
4. A hair curler comprising relatively rotatable parts provided with radial slots adapted to be moved into and out of register with each other, and means movable on one of said parts into and out of locking position with respect to said radial slots in registry position.
5. A hair curler comprising a tubular outer spindle provided with a locking recess, of an inner spindle journaled in the bore of said outer spindle and provided with a locking recess, and means movable within the recess in said inner spindle into and out of locking engagement with the recess in said outer spindle.
6. A hair curler comprising coaxially arranged relatively rotatable spindles, said spindles being provided with recesses movable into and out of registry with each other, and a finger-grip mounted on one of said spindles and movable into and out of locking position with respect to said recesses.
7. A hair curler comprising relatively rotatable spindles having portions arranged one within the other, said portions being provided with recesses movable into and out of registry with each other, and a finger grip movably mounted in the recess in one of said portions into and out of position to engage in the recess in the other of said portions.
8. A hair curler comprising relatively rotatable parts provided with radial slots movable into and out of register with each other, and a finger grip rotatable on axis into and out of position within said radial slots in registry position to lock said rotatable parts against relative rotation.
9. A hair curler comprising a tubular outer spindle provided with a locking recess, of an inner spindle journaled in the bore of said outer spindle and provided with a locking recess, and a finger grip pivoted within the recess in said inner spindle and movable from a position transverse to the common axis of said spindles to and from a position in which it rests within the locking recess in said outer spindle.
10. A hair curler comprising an outer tubular spindle having one end provided with radial recesses, an inner spindle journaled in the bore of said tubular spindle, said inner spindle being provided with an axial slot, and an element pivoted within the axial slot in said inner spindle and movable into and out of engagement with one or another of said radial recesses in the outer spindle.
11. A hair curler comprising a tubular spindle terminating at one end in a cylindrical flange provided with radial recesses, another spindle journaled in the bore of said tubular spindle and having a slotted end projecting axially beyond the recessed flange of said tubular spindle, and a finger grip pivoted within the slotted end of the inner spindle and movable from a transverse position in which it serves as a grip to rotate the inner spindle within the outer spindle to a position in which it is adapted to interlock with one or another of the recesses in the cylindrical flange of said tubular spindle.
12. A hair curler comprising an outer tubular spindle having one end provided with radial recesses, an inner spindle journaled in the bore of said tubular spindle and projecting axially beyond the radially recessed end of the outer spindle, said inner spindle being provided with a diametral slot, and means movable within said slot in the inner spindle into and out of position to rest in one of said radial recesses in the outer spindle.

LEOPOLD STEINER.
